UNITED STATES PATENT OFFICE.

WILLIAM M. BELL, OF PORTSMOUTH, OHIO.

AUXILIARY CONTAINER FOR TOILETS.

Application filed January 30, 1928. Serial No. 250,585.

This invention relates to a receptacle for use in connection with toilets of railway cars or the like, the primary object of the invention being to provide a receptacle secured 5 permanently to the car in a position to catch material from the toilet and prevent the deposit of the material on the tracks when the car is waiting in the station.

An important object of the invention is 10 to provide a receptacle of this character tapered towards the upper end so that should material freeze in the receptacle the material will be readily released and fall from the receptacle when the closure that 15 closes the lower end of the receptacle, has been moved to its open position.

A still further object of the invention is to support the receptacle in such a way that the upper end of the receptacle is spaced 20 from the bottom of the car so that obnoxious odors may pass from the receptacle and will not pass into the car.

With the foregoing and other objects in view which will appear as description proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawing:

Figure 1 is an elevational view illustrating a receptacle constructed in accordance with the invention as positioned under a 35 toilet of a car.

Figure 2 is a front elevational view thereof.

Figure 3 is a fragmental sectional view 40 through the receptacle and closure.

Referring to the drawing in detail, the reference character 5 designates the usual toilet of the type employed in connection 45 with railway cars and with which the device forming the essence of the present invention, is employed.

The device includes a receptacle indicated generally by the reference character 6, the 50 same being substantially large and as shown tapers towards the upper end so that the receptacle will be larger at the bottom than at the top.

Brackets indicated at 7 secure the receptacle 55 6 to the bottom of the car directly under the pipe 8 leading from the toilet, so

that the pipe 8 may discharge material thereinto.

These brackets 7 are of constructions so that the upper end of the receptacle 6 will 60 be held in spaced relation with the bottom of the car to ventilate the receptacle 6 and permit obnoxious odors to pass therefrom.

At the lower end of the receptacle is a band 9 which is formed of heavy material 65 and secured to the receptacle by means of the rivets 10. Extending from the band 9 is a circular rib 11 tapered to fit within the tapered groove 12 formed in the upper surface of the hinged closure 13 so that a tight 70 connection between the closure and band 9 will be insured at all times preventing leakage at this point.

The hinge by means of which the closure is connected with the receptacle, is indicated 75 at 14 and is disposed exteriorly of the receptacle.

Coiled springs indicated at 15 connect with the closure 13, at 16 and have their upper ends hooked into the eye bolts 17 secured adjacent to the upper end of the receptacle 6 with the result that the springs act to return the closure to its closed position when the closure has been operated or moved to its open position to dump the 85 contents of the receptacle.

Formed integral with the closure 13 is a depending arm 18 to which the flexible connecting member 19 is connected, one end of the member 19 being connected with the 90 bell crank lever 20, at 21. Connected with the opposite end of the bell crank lever 20 is a rod 22 supplied with a head 23 and affords means whereby the bell crank lever may be operated to move the closure 13 to 95 its open position.

Contacting with the rod 22 is a spring finger 24 that normally urges the rod 22 laterally to insure against the rod rattling while the car is in motion.

From the foregoing it will be obvious that due to the construction shown and described it will be unnecessary to lock the door of the toilet to prevent use thereof, since the closure 18 may be moved to its closed position 100 by the porter in charge of the car to the end that material will be caught in the receptacle 6 and when the train has left the station the closure may be moved to release the material in the receptacle 6.

It might be further stated that a notch 25 is formed at the upper end of the rod 22

and is adapted to engage the plate 26 to hold the rod to the limit of its downward movement so that the closure 31 may be held in its open position.

I claim:

In a device of the character described a body portion, brackets for securing the body portion to a supporting structure under the discharge pipe of a toilet, said brackets

adapted to support the upper end of the body portion in spaced relation with the supporting structure, a closure for closing one end of the body portion, and means for moving the closure to its open position.

In testimony that I claim the foregoing as my own, I have hereto affixed my signature.

WILLIAM M. BELL.
